UNITED STATES PATENT OFFICE.

JEREMIAH T. MINAHAN, OF AUDUBON, NEW JERSEY.

SAFETY RAZOR.

Application filed November 14, 1927. Serial No. 233,006.

This invention relates to shaving devices and more particularly to the type known as safety razors.

The objects of my invention are to provide 5 improved mechanism whereby the safety guards of a safety razor may be swung from the razor blade to free the blade for cleaning or sharpening and to provide such mechanism which is adapted for use with double 10 edged blades of the usual type without change in the operative position of the blade.

Other objects and features will be apparent from the following description read in conjunction with the accompanying drawings in 15 which:—

Figure 1 is a plan view of a razor incorporating my invention showing the top holding member superimposed over a blade.

Figure 2 is a side view of the razor showing 20 the relation of the adjustable guards to the blade and holding member.

Figure 3 is a central section through the razor with part of the adjusting mechanism broken away.

Figure 4 is a plan view of the razor blade 25 mounting with the blade and holding member removed.

Figure 5 shows the construction of the holding member.

Figure 6 is a front view of the razor illustrating 30 the construction of the adjusting mechanism in the handle.

Figure 7 illustrates a receptacle wherein the razor may be kept when not in use. The 35 pair of rolls accommodate an edge of the blade and constitute a sharpening means for the razor.

Figure 8 illustrates one form of arranging 40 the razor within a container with respect to the sharpening rolls.

Considering all the figures simultaneously, similar designations referring to similar parts, numeral 9 represents a razor having a handle 10 with a blade mounting 11 at one end 45 and integral therewith. Hinged to mounting 11 are guards 12. As indicated in Figure 4, the guards are arranged to link with the mounting. Pins connecting the guards and mounting constitute hinges whereon the 50 guards may be swung toward the handle. Pins 13 interconnect the guards and mounting and extend the whole length of the device, as is best shown in Figure 4.

Each guard is swiveled by means of arms 55 14 to a slide rod 15 housed within the handle.

The handle is provided with an opening therethrough for accommodating rod 15 and is slotted at 16. Button head 17 extends through the slotted portion and is threaded to the rod. A movement of the button will 60 therefore actuate the rod which in turn controls the guards through arm 14. By tightening the button, at any desired point in the slotted portion, the guards will be fixed in position and assume a desired angle with respect to the mounting member. 65

Integral with the mounting are provided 70 guide pins 18. A blade 19 having perforations therein spaced correspondingly to the guide pins of the mounting, is slipped over the pins and held to the mounting by holding member 20. Holding member 20 is arranged with orifices 21 having one portion thereof adapted to snugly engage pins 18, the remainder of each orifice being sufficiently 75 large to pass over the heads of the pins which are of greater diameter than the body of the pins. As is evident from Figure 1, each pin has an enlarged head. The perforations of the blade are sufficiently large to 80 pass over the heads. The thickness of the holding member is such that when the member is slid under the heads of the pins, the blade will be tightly held on the mounting.

In use, a blade will be superimposed over 85 the pins and the holding member secured in position under the heads to secure the blade in position. The button 17 will then be shifted in the slot until the guards are at a desired angle to the edges of the blade. A 90 turn of the button will fix the guards in position. If an unguarded edge is desired, the button will be slipped to the bottom of the slot and the guards will assume a position 95 adjacent the handle, as shown in Figure 8.

The drawings show the mounting and holding member of curved construction. By securing the blade in position, the blade will also be curved, as shown in Figures 2 and 3. It will be understood that the mounting 100 may be made flat so that the blade will present edges substantially perpendicular to a plane through the center line of the handle.

Figure 7 illustrates a pair of sharpening 105 rolls situated in a container wherein the razor may be kept when not in use. When the button is pulled down, the guards will assume the position shown in Figure 8, leaving the cutting edges exposed on both sides of the blade for a considerable distance from 110

the edge to the center of the blade. By moving the edge between the rolls, the blade may be sharpened.

- 5 The rolls are rotatably mounted on suitable supports 22 and are normally in contact with each other. When the blade descends between the rolls, one of them designated by numeral 23 in Figure 8 will recede from its position due to support 22 being slidably 10 arranged within a mounting slot 24. Leaf spring 25 is arranged to return the roll to its normal position in contact with its associated roll when the blade is withdrawn from between the rolls.
- 15 Various modifications may be made in the design of the razor and holding device without departure from the mechanical features called for by the claims.

What I claim is:—

- 20 1. In a safety razor, a handle bored and slotted for part of its length; a blade mounting fixed to take through the holes in a double edged safety razor blade, the holder having a fixed central part extending longitudinally of the blade and materially narrower than the blade, a curved holding member materially narrower than the blade 40 having a fixed central part extending longitudinally of the blade and materially narrower than the blade, a curved holding member materially narrower than the blade 45 adapted to clamp a razor blade to the blade mounting; curved guards hinged to the sides of the blade mounting; a rod slidable in the bore of the handle; means for locking the slide rod in adjusted position, and links connecting the guards with the slide rod whereby, by actuation of the slide rod, the guards may be swung from alignment with the blade holder into a position adjacent the handle or may be swung in reverse direction. 50
- 25 3. In a safety razor, a handle bored and slotted for part of its length; a blade mounting fixed to one end of the handle, having a fixed central part materially narrower than the blade; headed pins extending from the fixed part of the blade holder and adapted to take through the holes in a double edged safety razor blade; a blade holder, materially narrower than the blade, having perforations with a diameter sufficient to pass over the heads and narrower extensions adapted to slide over the pins and clamp the holder and 55 blade to the blade mounting; a rod slidable in the bore of the handle; means for locking the slide rod in adjusted positions, and links connecting the guards with the slide rod whereby, by actuation of the slide rod, the guard may be swung from alignment with the blade holder into a position adjacent the handle or may be swung in reverse direction. 60
- 30 4. In a safety razor, a handle bored and slotted for part of its length; a curved blade mounting; a rod slidable in the bore of the handle; means for locking the slide rod in adjusted position, and links connecting the guards with the slide rod whereby, by actuation of the slide rod, the guards may be swung from alignment with the blade holder into a position adjacent the handle or may be swung in reverse direction. 65
- 35 5. In a safety razor, a handle bored and slotted for part of its length; a curved blade mounting; a rod slidable in the bore of the handle; means for locking the slide rod in adjusted position, and links connecting the guards with the slide rod whereby, by actuation of the slide rod, the guards may be swung from alignment with the blade holder into a position adjacent the handle or may be swung in reverse direction. 70

2. In a safety razor, a handle bored and slotted for part of its length; a curved blade

mounting fixed to take through the holes in a double edged safety razor blade, the holder having a fixed central part extending longitudinally of the blade and materially narrower than the blade, a curved holding member materially narrower than the blade 40 adapted to clamp a razor blade to the blade mounting; curved guards hinged to the sides of the blade mounting; a rod slidable in the bore of the handle; means for locking the slide rod in adjusted position, and links connecting the guards with the slide rod whereby, by actuation of the slide rod, the guards may be swung from alignment with the blade holder into a position adjacent the handle or may be swung in reverse direction. 55

3. In a safety razor, a handle bored and slotted for part of its length; a blade mounting fixed to one end of the handle, having a fixed central part materially narrower than the blade; headed pins extending from the fixed part of the blade holder and adapted to take through the holes in a double edged safety razor blade; a blade holder, materially narrower than the blade, having perforations with a diameter sufficient to pass over the heads and narrower extensions adapted to slide over the pins and clamp the holder and blade to the blade mounting; a rod slidable in the bore of the handle; means for locking the slide rod in adjusted positions, and links connecting the guards with the slide rod whereby, by actuation of the slide rod, the guard may be swung from alignment with the blade holder into a position adjacent the handle or may be swung in reverse direction. 75

In testimony whereof I have signed my name to this specification.

JEREMIAH T. MINAHAN.
